Attorney

UNITED STATES PATENT OFFICE.

ALPHONSE F. MONEUSE, OF VALLEY STREAM, NEW YORK.

WATER HEATER.

Application filed December 2, 1925. Serial No. 72,783.

This invention relates to a water heater, and more particularly to that type of heater wherein the heater is associated with the ordinary house boiler or storage tank, for the purpose of furnishing hot water quickly in hot season, without the necessity of operating the steam or hot water boiler as the case may be, but at the same time is so constructed and so connected with the boiler, that the boiler 5 may serve at times as the means for heating the water in the heater, as for instance in the winter, or in cold weather when the furnace is being operated.

The object of the invention is to provide 15 a very simple and durable construction, which may be conveniently connected with the steam or hot water boiler, and with a storage tank, and which may be readily cut off from the boiler according to requirements, 20 and when so cut off the water in the heater may be quickly heated by a flame from a gas burner, kerosene burner, or in fact from any suitable source of heat.

It will be understood that throughout the 25 following descriptions the term boiler will mean the steam or hot water boiler usually located in the basement or cellar of the house or building, and by the term "storage tank" I mean that part of the apparatus which is 30 usually designated as the kitchen boiler.

A further object of the invention is to so construct the heater that it virtually becomes a part of the whole apparatus, and the arrangement is such that the heater may if 35 desirable, operate in connection with the hot water boiler, and the flame at the same time, or individually, as the operator may elect, since it may be advantageous in certain moderate weathers when the hot water or steam 40 boiler is not being forced, to use both the flame and the water from the hot water boiler at the same time. However, as before intimated in summer, the heater will be cut off from the hot water boiler, and the flame depended upon solely for supplying the hot 45 water from the heater to the storage tank.

The heater is installed close to the boiler, but the storage tank may be located in the kitchen or in any other suitable place in the building, and while I have shown the valve 50 for controlling the fuel-feed to the burner, it will be understood that this valve may be located in any part of the house or building so that the heating flame of the burner may be controlled at a distance from the heater. The burner may be of any approved construc-

tion, but preferably a gas burner where gas is available, in which case the burner would have associated with it a pilot, from which the heating gas of the flame is ignited when 60 it is required.

In the drawings:

Figure 1 is a view partly in section and partly in elevation, the part in section showing a portion of a steam or hot water boiler. 65

Figure 2 is a vertical section of the heater.

Referring to the drawings, the numeral 1 designates a boiler. Connected with the boiler by pipes 2 and 3, is the hot water heater 4. This comprises two casings, an 70 outer casing 5, and an inner casing 6, the outer casing being spaced from the inner casing, thus providing two water chambers 7 and 8, the space forming the chamber 8 being 75 narrow, so that the water in said chamber will heat quickly. The pipe 2 is let into the top of the chamber 7, and the pipe 3 is let into the bottom of said chamber, as clearly shown in Figure 2, and let into chamber 8, respectively at the top and bottom thereof, are pipes 80 9 and 10. The pipe 9 communicates with the top of the storage tank 9', and pipe 10 is connected to the bottom of said tank.

The pipes 2 and 3 are each provided respectively, with valves 11 and 12 by which 85 the heater may be entirely cut off from the boiler, as for instance in summer or warm weather, or by which at proper times communication may be established between the boiler and the inner chamber 7.

The numeral 12' designates a conventional burner which is connected with a fuel pipe 13, controlled by valve 14. This burner may be of any convenient type or form and the fuel employed may be any suitable kind, 95 usually used for heating purposes, and as before intimated, where gas is used, the burner is preferably equipped with a pilot, and is provided with the usual air or mixing chamber, designated by *a*. 100

Connected with the bottom of the casing 6 is a pipe 15 whose outer end is provided with a drain cock, 16, by which the water may be drained from the chamber of the inner casing, as might be desirable in mild or warm weather when the steam or hot water boiler is not being operated, and when it is desirable to use only the water space surrounding said inner casing.

The heater is enveloped by a hood 17, open 110 at its bottom as indicated at 18. Perforations 19 are provided at the top of the hood

for the escape of gases or the products of combustion from the burner, after the heat thereof has been utilized to heat the water in the outer casing.

5 In summer when the boiler is not in operation, it is obviously not desirable to have within the inner chamber a body of dead cold water, and hence the drain pipe 15 is provided, which drain pipe is used to drain the 10 water from the inner heating chamber or casing when the valves 11 and 12 are closed to cut off communication between the boiler and said heating chamber.

The numeral 20 designates the feed pipe 15 for the storage tank, which pipe it will be understood, is suitably connected with the water main. Through this pipe the water passes into tank 9'. The numeral 21 designates the outlet pipe, which is the usual pipe 20 which leads to the house outlets.

The pipe 2 is let into the hot water or steam boiler at or a little below the water line, and the pipe 3 is similarly let in into the boiler below the water line, so that when the valves 25 11 and 12 are opened the chamber 7 of the heater will be in communication with the boiler and consequently filled with water. At such times it will be understood the burner 12 need not be lighted and the intensely hot 30 water in the inner chamber of the heater from the boiler, serves as the medium for heating the water in the chamber 8. However, when the boiler is not in operation, as in warm weather, the chamber 8 or thin space between the inner and outer casings 5 and 6 is 35 filled with water to be heated by the flame

from the burner 12. When the burner 12 is lighted the water in chamber 8 will be brought quickly to a very high temperature and will be caused to circulate through the 40 pipes 9 and 10, and consequently the storage tank 9', wherefrom it may be drawn to the house outlets through the outlet pipe 21.

It will be understood that water is always 45 in the chamber 8, of the heater, since it is always in communication with the storage tank, but as before intimated the water may be drained from the inner chamber 7 without putting the heater out of commission.

Claim:

In combination with the water chamber of a boiler, a storage tank, a water heater interposed between said boiler and tank, said heater comprising inner and outer casings, providing inner and outer water chambers, valve 55 connections between the boiler and the inner chamber thereby enabling said inner chamber to be entirely cut off from the boiler, connections between the outer chamber of the heater and the storage tank whereby when 60 the water is heated in the outer chamber it will be caused to circulate into and through said storage tank, means for draining the inner heating chamber, and means for supplying heat to the outer casing when it is desired to augment the heat in the outer chamber or to alone heat the water in said outer 65 chamber.

In testimony whereof he has affixed his signature.

ALPHONSE F. MONEUSE.
